UNITED STATES PATENT OFFICE.

WILLIAM COBB SMITH, OF AMESBURY, MASSACHUSETTS.

PISTON-RING.

SPECIFICATION forming a part of Reissued Letters Patent No. 12,225, dated May 24, 1904.

Original No. 757,085, dated April 12, 1904. Application for reissue filed April 28, 1904. Serial No. 205,428.

To all whom it may concern:

Be it known that I, WILLIAM COBB SMITH, a citizen of the United States, residing at Amesbury, in the county of Essex and State of Massachusetts, have invented certain new and useful Improvements in Piston-Rings, of which the following is a specification.

My invention relates to improvements in piston-rings of hydrocarbon-motors.

10 The principal object of the invention is to provide a metallic packing-ring which will expand in the cylinder without losing in efficiency.

15 A further object is to provide independent means for securing the necessary pressure against the cylinder-walls.

20 As far as I am aware the following are novel features in a piston-ring—viz., a spiral ring divided transversely into several parts and 25 said parts being in close end-to-end contact, a spiral ring having but little resiliency in itself, but provided with an independent spring for producing the necessary pressure against the cylinder-walls, a spiral ring and a spiral 30 peripheral piston-groove to receive said ring, a spiral ring having a free end in contact with a spring, whereby the ring may always accommodate itself to differences in ring and cylinder expansion, and a spiral ring having 35 a stop at one end to prevent rotation about the piston.

In the drawings, Figure 1' is a side view. Fig. 2 is a central vertical longitudinal section in plane of line L'', Fig. 3. Fig. 3 is a 35 vertical transverse section in plane of line L', Fig. 2. Fig. 4 is a side view, and Fig. 5 a horizontal longitudinal section, in plane of line I', Fig. 4.

In the drawings the same letters refer to 40 like parts.

A represents the piston, R the connecting-rod, and P the connecting-rod pin.

B represents a piston-ring, and W a wide portion of said ring.

45 S' represents a slot, and G a spiral groove, in the piston-periphery.

H represents the wall of groove G, a part 50 of which is cut away to receive the wide portion W of the ring. The ring B is adapted to fit closely in the groove G, and the wide

portion W conforms with the shape of groove G at one end.

The ring B is divided into segments which are not necessarily of uniform length. The ends of the segments may be cut square, as 55 shown, or in any suitable manner.

T represent the divisions in the ring B or the contacting ends of the segments.

S represents a straight wire spring shoul- 60 dered to receive the ring B. The spring S is also tapered, to fit a hole in the wall of the piston A. The action of the spring S in the slot S' is shown by dotted lines.

The lines m and n pass through the contact- 65 ing ends of segments a and b and represent lines of force from the spring S. Since m and n are not in the same straight line, the segments a and b are not only maintained in close mutual contact, but in close contact with the cylinder-walls by the pressure of spring 70 S. Thus each segment of the ring B is maintained in perfect contact with the cylinder- 75 walls, the degree of pressure being governed by the tension of the spring S. The ring B is divided into segments in order to overcome the evil effects of contortion by heat. The wide portion W of the ring B is provided to close the opening between the wall H of the piston-groove and the cylinder-walls. The end of groove G at W is a stop for ring B. 80 Having no slit or opening, this ring cannot lose in efficiency by wear.

I I' I'' and L L' L'' are broken lines in the 85 several views.

Having thus described my invention, what I claim, and desire to secure by Letters Patent, is—

1. In a piston, a spiral peripheral metallic 90 packing-ring, a spiral peripheral groove adapted to receive said ring, a stop at one end of said groove, and means for maintaining said ring in close contact with said stop.

2. In a piston, a spiral peripheral metallic 95 packing-ring divided in several parts, a spring secured in said piston adapted to maintain said parts in close end-to-end contact, and said spring also adapted to maintain said parts in close contact with the cylinder-walls.

3. In a piston, a spiral peripheral metallic 100

- packing-ring divided transversely in several parts, each part being less than a turn of the spiral, a spiral peripheral groove in said piston having a stop at one end, a spring secured in said piston adapted to maintain said ring in close contact with said stop, and said spring also adapted to maintain said parts in close end-to-end contact, and in close contact with the cylinder-walls.
4. In a piston, a spiral peripheral metallic packing-ring divided transversely in several parts, each part being less than a turn of the spiral, a spring secured in said piston adapted

to maintain said parts in close contact, a spiral peripheral groove in said piston adapted to receive said ring, a cut-away portion in the groove-wall at one end, and a widened portion of the ring adapted to fit into said cut-away portion, substantially as and for the purposes set forth.

In testimony whereof I affix my signature in presence of two witnesses.

WILLIAM COBB SMITH.
